C. C. Shepherd

ATTORNEY

UNITED STATES PATENT OFFICE.

STILLMAN W. ROBINSON, OF COLUMBUS, OHIO, ASSIGNOR OF ONE-HALF TO
THE WIRE GRIP FASTENING COMPANY, OF BOSTON, MASSACHUSETTS.

NAILING-MACHINE FOR BOOTS OR SHOES.

SPECIFICATION forming part of Letters Patent No. 416,272, dated December 3, 1889.

Application filed January 15, 1889. Serial No. 296,451. (No model.)

To all whom it may concern:

Be it known that I, STILLMAN W. ROBINSON, a citizen of the United States, residing at Columbus, in the county of Franklin and 5 State of Ohio, have invented a certain new and useful Improvement in Nailing-Machines for Boots or Shoes, of which the following is a specification.

My invention relates to nailing-machines, 10 and particularly relates to machines for nailing boots or shoes.

The objects of my invention are to provide a machine of this class of such construction as to cause the driver to descend a definite 15 and uniform distance when striking the driving-blows; to construct the same so that when once properly adjusted it will remain permanently in adjustment to enable the driver to make quick and powerful blows in rapid succession; to so construct the machine that the 20 excess of force of a blow remaining when a nail is driven shall be quietly and harmlessly spent; to insure the complete driving of the nail, and to accomplish the same in a simple, 25 noiseless, and effective manner. These objects I accomplish in the manner illustrated in the accompanying drawings, in which—

Figure 1 is a view in elevation of my machine. Fig. 2 is a view at right angles with 30 that shown in Fig. 1, and Fig. 3 is a view taken on line $x-x$ of Fig. 1.

Similar letters refer to similar parts throughout the several views.

This invention consists, essentially, of a 35 driver-rod pressed downward by spring-tension and raised by a pitman and crank so arranged that when the crank is turned past its upper dead-center it is released, and by tension of said spring is brought to its lower 40 dead-center or farther, thus forcing the driver-rod against a nail placed in such position as to receive the blow.

a represents the standard or vertical frame of my machine, which may be of any desired 45 form, but preferably has its upper portion b bent forward and thence downward a short distance, as shown.

c represents a crank having its shaft c' pivotally supported in suitable bearings formed 50 in the body of the standard a at a point preferably slightly above and at one side of an imaginary horizontal line drawn through the

termination of the outer bent portion b . Pivotally connected with the crank-pin c^2 of the crank c , which extends beneath the bent portion b of the standard, is the upper end of a pitman d , the pin c^2 being of such length as to project a short distance through said pitman-head, as shown. 55

e represents a shaft pivoted horizontally in the outer end of the bent portion b of the standard and having mounted on its outer end a belt-wheel f . Made to project from the inner end of the shaft e , at right angles therewith, is a finger or arm g , preferably slightly curved, as shown, and of a length preferably slightly greater than the main arm c of the crank. 60

The lower or outer end of the pitman is slotted or divided to receive the upper end of 70 a vertical driving-rod h , which is pivoted therein, and which, being approximately parallel with the standard a , bears loosely in eyes formed in the outer ends of one or more guide-arms a' , projecting outwardly from the 75 standard. Made to extend from the standard at a point about opposite the lower end of the pitman and in a direction at right angles with the guide-arm a' , and being then bent forwardly in the direction of said arms 80 a' to a point beyond the pitman-head, is a rod i . Coiled about the rod i and having its outer end rigidly secured to the outer end of said rod is a coiled spring k , the remaining 85 or inner end of which projects through the slot in the lower end of the pitman and rests upon the head of the driving-rod, as shown. In the lower end of the driving-rod is formed a socket, into which may be inserted and held, by one or more set-screws or otherwise, a 90 driving pin or head m . The work n , into which the nails are to be driven, may be supported in such position that the hammer may strike the nail by supporting the same against a suitably-shaped nose p , made to project 95 from the standard a , to which it is secured, or it may be supported in any other desirable way. The standard a may be provided with a suitable foot or base, which may rest upon the floor, or may be formed, as shown, with 100 perforated projecting ears or lugs q , by means of which the standard may be secured to a wall or post at any desired height.

The operation of my machine is as follows:

Motion having been communicated to the belt-wheel in the usual manner, it will be seen that the revolution of its shaft will cause the revolution of the finger *g*, fixed thereon.

- 5 For illustration, I will suppose the crank-pin *c* to be at its lower dead-center and the finger *g* approaching it. The finger being in motion, as above described, it will be seen that it will be brought into contact with the crank-pin *c*² and force the latter upward until past its upper dead-center, at which point the tension of the spring *k* will cause the crank-pin to leave the finger and force said crank-pin, pitman, and driver quickly downward.
- 10 This downward movement of said parts will cause the driver-head *m* to descend the exact distance fixed and determined by the length of the parts to drive home the nail *r*, which is supported in proper position to receive the blow.
- 15 If an excess of force is imparted by the spring, the crank will pass its lower dead-center and raise the driver against the spring until the crank is arrested, when it will return toward the lower dead-center and oscillate in decreasing arcs until at rest. The continued steady motion of the shaft *e* will cause the finger *g* to soon again come into contact with the crank-pin *c*², when the latter will be again raised and another blow struck, as above de-
- 20 scribed. The nails are thus driven in rapid succession, suitable mechanism being employed to feed the work along and to support the nails in position to receive the blows. The work or shoe being nailed may be mounted
- 25 in the usual way on a jack, or it may be supported on a horn. In case a horn is used to support the work, which is stationary at a fixed height above the floor, it may be necessary, on account of the thickness of the work
- 30 to be nailed, to release the frame and fix it at a higher or lower point.
- 35 It is obvious that the herein-described machine may be utilized not only for driving loose nails, but for driving ordinary shoe pegs or nails formed from continuous wire. It may be employed for any other purpose where it is desired that quick decisive blows should be struck. It is also obvious that the finger *g* may be made shorter than shown, or of such
- 40 length that owing to its being held eccentrically with relation to the crank *c*, as shown

in Fig. 3 of the drawings, it will escape the crank-pin before the latter reaches its upper dead-center and allow the crank to drop back again from tension of the spring and thus 55 produce the blow.

Other means than those herein employed may be used to impart motion to the crank to raise the latter from its lower dead-center for the purpose of producing the blow. 60

Having now fully described my invention, what I claim, and desire to secure by Letters Patent, is—

1. In a nailing-machine, the combination, with the frame *a*, its crank *c*, pitman *d*, pivoted to said crank, and spring-actuated driver *h*, pivoted to said pitman and passing through guides *a'*, of the driving-shaft *e*, pivoted, as described, in the frame, carrying on one end the finger *g*, substantially as and for the purpose specified. 65

2. In a nailing-machine, the combination, with a frame *a*, crank *c*, pitman *d*, pivoted to said crank, driver *h*, pivoted to said pitman, and an operating mechanism therefor, of a spring *k*, adapted to force said parts downward, substantially as and for the purpose specified. 75

3. In a nailing-machine, the combination, with a frame *a*, crank *c*, pitman *d*, pivoted to said crank, driver *h*, pivoted to said pitman, the latter passing through guides *a'*, and having a detachable head *m*, and operating mechanism therefor, of spring *k*, supported on arm *i*, said spring having its loose end bearing in 85 the lower end of the pitman *d* and upon the head of the driver *h*, substantially as and for the purpose specified.

4. In a nailing-machine, the combination, with the frame, of the crank *c*, pitman *d*, pivoted to said crank, driver *h*, pivoted to said pitman and having detachable head *m*, and spring *k*, pressing upon said driver, with the driving-shaft *e* pivoted, as above described, in the frame, carrying on one end thereof the finger *g*, substantially as and for the purpose specified. 90

STILLMAN W. ROBINSON.

In presence of—

C. C. SHEPHERD,
BARTON GRIFFITH.
